AIR-CONDITIONED OXYGEN-BOX

Oscar Randolph Batson, Bailey F. Moore, and Amos U. Christie, Nashville, Tenn.

Application July 28, 1952, Serial No. 301,344

12 Claims. (Cl. 128—1)

This invention relates to an air-conditioned oxygen-box. More particularly it relates to a small open-top air-conditioned oxygen-box which is easily adaptable to babies, children or adults.

Oxygen tents or enclosure of the prior art have been generally unsatisfactory. Physicians and nurses have found them cumbersome and unreliable for maintaining therapeutic oxygen concentrations. Patients have found them treatment-wise ineffective, and psychologically oppressive in interfering with visibility and in producing a "closed-in" feeling.

It is the purpose of this invention to produce an oxygen box that is open above the patient's head, is transparent at the sides and front, includes refrigerating means for cooling the air, maintains desired oxygen concentration with low oxygen consumption, effectively humidifies the air by simply introducing the oxygen thru a nebulizer, is inexpensive in initial cost and in upkeep, is compact and easy to handle and set up, and is quickly and easily adaptable to patients of all sizes. These and other objects and advantages of the invention will become apparent as the following detailed description proceeds.

In the drawings, in which like reference characters refer to the same parts in the several views:

Fig. 1 is a perspective view from above and behind an oxygen box according to this invention.

Fig. 2 is a plan view of the oxygen box.

Fig. 3 is an elevational view of the right side of the device.

Fig. 4 is a front elevation.

Fig. 5 is a partial side elevational view in section taken on the line 5—5 of Fig. 7.

Fig. 6 is an enlarged detailed elevation of the nebulizer-humidifier.

Fig. 7 is an enlarged detailed elevation in section on the line 7—7 of Fig. 4.

With reference now to the drawings, the numerals 1—4 respectively designate the front, the rear and the left and right side panels of the box. These panels 1—4 are preferably formed of rigid sheets of colorless transparent plastic material, altho glass panels could be used, if desired. The panels may be joined at their corners by cementing or thermo-plastic welding with or without added reinforcing (such as corner posts 5). It is preferred that a bottom panel 7 of the same plastic material, or of plywood, etc., be used for its rigidifying effect on the vertical walls 1—4 of the box.

Approximately a fourth of the volume of the box is partitioned off from the remainder thereof by a partition 9, preferably formed of stainless steel or aluminum. Partition 9 may be fastened to the side panels 3 and 4 by screws 11 passing thru holes in the forwardly bent integral flanges 9'. Partition 9 may constitute the front face of an ice-receptacle 13, or alternatively, ice-receptacle 13 could be made separate from partition 9 and be (removably) mounted thereon. The former construction produces a good heat-exchange relationship between the ice-receptacle and the treatment chamber. The ice-re-

2

ceptacle 13 has a centrally dished bottom and a drain pipe 15 discharging to the outside thru the rear wall 2. It may have a separate cover 14, or it may extend upwardly so as to have its upper edge flush with the top 5 of the box proper, so that the forwardly hinged cover 15, including handle 17, for the partitioned-off space, can also serve as a cover for the ice-receptacle 13. A drip pan (not shown) may be placed beneath the ice-receptacle 13 to catch condensed moisture.

10 Beside the ice-receptacle 13 and also supported from and by the partition 9 is the combined oxygen and humidity-supplying apparatus, generally designated 21. Apparatus 21 comprises a support plate 23 removably hung by bayonet-type openings on headed posts 25. Support 15 plate 23 carries a receptacle 27 for a removable water reservoir 29, which is connected to the nebulizer 31 by a water-supply tube 33. Nebulizer 31 (Figs. 5 and 6) is supported from plate 23 by one or more brackets 35 connected to plate 23 and to the screw-top 37 of the nebulizer. The float chamber of the nebulizer 31 is a glass jar 39 screwed up into the top 37. Water is maintained at the desired level by a conventional valve 41 controlled by the float 43. By the use of a filter (or pure-water ice) it would be possible to use the water 20 from the melted ice as the water supply for the nebulizer, when water is the sole liquid being atomized.

Oxygen is supplied to the nebulizer by a hose 45 (which may, if desired, have a wall-mounted safety coupler 46 between its external and internal sections). Hose 45 30 connects to tube 45' (Fig. 6) which conducts the oxygen to the atomizer 47. An adjustment screw 49 controls the supply of water sucked thru pipe 51 by the force of the oxygen stream, to issue thru jet 53 as an oxygen-borne mist for discharge thru pipe 55 into the oxygen box. Supply hose 45 connects to the usual oxygen-flow control-valve mounted on the oxygen tank (both not shown).

The already heavier-than-air oxygen is made still more heavy by being (evaporatively) mist-cooled as it issues from the nebulizer. It therefore tends to settle to the 40 bottom of the treatment chamber, where it is needed, while the warm exhaled air tends to be blown, and naturally to rise, to the top of the box for discharge into the room. Thus the many advantages of an open-topped box may be obtained at a very small cost in terms of 45 loss of oxygen. It has been found that an oxygen concentration of 72% (volumetric) can be maintained 4 inches from the bottom with an oxygen consumption of only 5 liters per minute. Three inches below the top the concentration will be about 67%, and at the top, 37%.

50 The front panel 1 of the box is provided with a semi-circular opening of a size to accommodate the waist or chest of a child. Babies may be placed lengthwise of and completely within the treatment chamber. With adults, usually the head only is inserted thru the opening. The 55 opening in panel 1 is bounded by a flanged rim 61 (Fig. 7) which securely holds an arch-shaped angle-strip or sleeve-shaped curtain 63 of plastic, oiled silk, or other air-tight sheeting, by means of a spring 65 (or other draw-string type of means) inserted in or over the edge 60 of said curtain 63. Curtain 63 may additionally have at its far end an elastic band or draw string (not shown) to improve its body-embracing action and thus eliminate loss of oxygen.

While we have disclosed a preferred embodiment of 65 our invention, by way of illustration, it is to be understood that many changes can be made in the size, shape, arrangement and composition of the parts without departing from the spirit of the invention defined by the subjoined claims.

70 Having thus described our invention, what we claim as new and desire to secure by Letters Patent of the United States is:

1. An open-top oxygen box comprising: rigid front, rear and side wall panels, said front and side wall panels being formed substantially entirely of transparent plastic material, the lower central portion of said front wall panel being cut away to form a body-receiving opening; a flexible curtain closing said opening and being adapted to surround the neck or waist of a patient having his head or chest in said box; means housed entirely within said box for cooling the air in said box; and nebulizer means attached to and carried by said box for simultaneously supplying the atmosphere in said box with a treatment gas and a liquid mist.

2. A device according to claim 1 and additionally comprising a bottom panel for firmly holding the other panels in assembled positions.

3. A device according to claim 1 and in which said flexible curtain is formed of a clear transparent plastic to minimize the psychological effect of being closed-in.

4. A device according to claim 1 and in which said curtain is in the form of a sleeve and includes a flexible draw-means for quickly removably attaching it to said front panel.

5. A device according to claim 4 and additionally including an arch-shaped angle-strip spanning the lower portion of said front panel and attached to the front face thereof, said panel having an opening therein conforming to the area encompassed by said angle-strip, said angle-strip and said panel together defining a channel for the draw-means of said sleeve.

6. A device according to claim 5 and in which said draw-means is a coil spring.

7. A device according to claim 1 and in which said means for cooling is a receptacle for ice.

8. A device according to claim 7 and additionally comprising a partition partially separating said box into a

relatively large front compartment and a relatively small narrow rear compartment, said rear compartment housing said ice receptacle.

5. A device according to claim 1 and in which said nebulizer means includes a liquid reservoir, a liquid supply conduit and a float-operated valve in said reservoir and valving said conduit for maintaining desired liquid level in said reservoir.

10. A device according to claim 9 and additionally comprising a supply reservoir above and connected to said valve by a conduit, said nebulizer means and said supply reservoir being mounted on a vertical panel adapted for quick-detachable mounting on an inner surface of said box.

15. 11. A device according to claim 10 and in which said surface is the rear surface of a partition across the rear portion of said box, said partition defining a space for receiving said nebulizer and a box for holding space-cooling ice or the like.

20. 12. A device according to claim 1 and in which said nebulizer means is adapted to discharge its gas and mist near the bottom of said box and remote from said curtain, whereby highest concentrations of medicaments are produced near the bottom of said box and loss thereof thru said curtain is minimized.
